US0D1032509S

(12) **United States Design Patent** (10) **Patent No.:** **US D1,032,509 S**
(45) **Date of Patent:** **** Jun. 25, 2024**

(54) **DOCKING STATION**

(71) Applicant: **MTD Products Inc**, Valley City, OH (US)

(72) Inventors: **Veronica Flanigan**, Broadview Hts, OH (US); **Jonathan Prybor**, Cleveland, OH (US); **Dennis Wayne Fowler**, Valley City, OH (US)

(73) Assignee: **MTD Products Inc**, Valley City, OH (US)

(**) Term: **15 Years**

(21) Appl. No.: **29/780,350**

(22) Filed: **Apr. 23, 2021**

(51) LOC (14) Cl. **13-02**

(52) U.S. Cl.

USPC **D13/108**; D15/17

(58) **Field of Classification Search**

USPC D13/103, 107, 108, 109, 110, 118, 119; D14/432, 434; D15/17

CPC H02J 7/0044; H02J 7/0045; H04B 1/3883

CLAIM

We claim the ornamental design for a docking station, as shown and described.

DESCRIPTION

FIG. 1 is a perspective view of a docking station showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines depict portions of the docking station that form no part of the claimed design.

1 Claim, 7 Drawing Sheets
